UNITED STATES PATENT OFFICE.

WILLIAM C. BURRELL, OF KANKAKEE, AND ROBERT R. ROBERTSON, OF CHICAGO,
ILLINOIS.

BAR-SUPPORTING PIN.

Application filed December 10, 1923. Serial No. 679,630.

To all whom it may concern:

Be it known that we, WILLIAM C. BURRELL and ROBERT R. ROBERTSON, citizens of the United States, respectively, residing at 5 Kankakee, in the county of Kankakee and State of Illinois, and at Chicago, in the county of Cook and State of Illinois, have invented certain new and useful Improvements in Bar-Supporting Pins, of which 10 the following is a specification.

The invention relates to improvements in bar supporting pins for holding reenforcing bars, in the manufacture of concrete roadways, elevated above the surface which the 15 conglomerate is intended to cover.

One of the objects of the invention is to provide a pin having a gage or stop to determine the height of the bar holding part above the ground surface.

20 A further object is to provide a one-piece sheet metal structure having a pointed, transversely curved end to enter the ground, laterally extending feet serving as a gage and as supports when in contact with the 25 ground surface and bar holding means at its top end to receive a horizontally disposed bar.

Another object is to provide a pin, substantially as described, having an additional gage part to determine its position 30 with respect to a side wall to support a bar parallel with said side wall and parallel with the ground surface adjacent said side wall.

A further object is to generally improve 35 means for holding and supporting reenforcing bars.

Other objects and advantages will become 40 readily apparent from a consideration with the following description when considered in connection with the accompanying drawings forming a part hereof, wherein:—

Fig. 1 is a transverse section taken thru 45 a bar or tube and thru the vertical side wall showing the bar gauging and supporting device in place.

Fig. 2 is a side elevation of one form of the device with both members thereof in the same longitudinal plane.

Fig. 3 is a view similar to Fig. 2 showing 50 the device at 90 degrees from Fig. 2.

Fig. 4 is a top plan view of the device, shown in Figs. 2 and 3.

Fig. 5 is a modification of Fig. 4.

Fig. 6 is an elevation of the device with the horizontal member shown in Fig. 1 removed. 55

Fig. 7 is a top plan view thereof.

In all the views the same reference characters are employed to indicate similar parts. 60

In Fig. 1 a channel bar 10 constituting a vertical side wall to define the limits of the conglomerate or concrete for the roadway is laid along the way where the road is to be constructed. 65

A reenforcing bar or tube 11 to be embedded in the concrete is to be supported a uniform distance from the ground surface 12 and spaced a uniform distance from the vertical side wall 10. 70

The supporting and gaging pin shown in Figs. 2 and 3 has two attached members 13 and 14, similar in general configuration, joined together by the thin flat integral strip 15. With this exception the two members 75 are of a channel formation throughout as more clearly shown in Fig. 4. Each member 13 and 14 has two prongs 16 and 17 providing a groove or concaved surface 18 at the extreme end of each member. When 80 the member 13 is bent at 15, so that said member 13 is in a plane substantially at right angles to the member 14, when the latter is driven into the ground the surfaces form a circle and embrace a round or square 85 bar or tube 11. The member 13 with its outer end in contact with the wall of the channel bar 10 determines the location where the member 14 shall be pushed or driven into the ground. 90

Intermediate the pointed end 14' and the remote end of the member 14 are two laterally projecting feet 19—19. These flat feet are for contact with the ground when the point 14' is pushed or driven into the 95 ground. They serve as a gage to determine the height of the upper end of the bar supporting pin from the ground surface.

At intervals, between the pins as described 100 having two joined members, one for spacing the other from a vertical side wall, the pin having only one member, the member 14, may be used for supporting the bar in which event the prongs 16 and 17 may be bent over the top of the bar, as shown by dotted lines. 105

The pin illustrated in Fig. 6 shows a lon-

gitudinal crimp, at 20, to give greater strength to the pin to resist laterally applied stress.

Below the feet 19 the part 14' of the pin 5 to be driven into the ground is pointed. The feet 19 not only serve as a gage but they also resist lateral movement of the pin and therefore the pin is maintained in a substantially vertical position and, furthermore, the weight of the bar cannot cause the 10 pin to sink deeper into the ground. The pin in either form is made of sheet metal, preferably, galvanized iron.

The device may quickly be placed in position and easily and quickly be secured to 15 the bar.

In the form shown in Fig. 6 the prongs 16 and 17 may be made sufficiently long to lap over two bars, as where the ends thereof 20 are superposed, one above the other. Where the bars overlap at their ends the form of device shown in Fig. 6 is always used. The alternative form shown in Figs. 1 and 3, 25 inclusive, is used at intervals along the bar to preserve true parallel alignment with the side wall 10.

Having described our invention what we claim as new and desire to secure by Letters Patent, is:—

30 1. A bar support comprising a pin of channel shape thruout having out-turned feet near its longitudinal mid-portion and a concave part at its upper end to receive a bar.

2. A bar support comprising a pin of 35 channel formation thruout with a longitudinally extending crimp within the channel, a stop near its mid-portion to determine the height of the support thereabove and a bar support at its upper end. 40

3. A bar support comprising a pin of channel formation thruout; feet turned outwardly from said side members at substantially right angles from the body of the pin near the mid-portion thereof and a receptacle to receive the bar at the upper end of the pin. 45

4. A bar support comprising a pin member; laterally extending feet near the mid-portion of the pin; a laterally extensible 50 member, and bar clamping means between the members to engage and hold the bar when said member is extended at substantially right angles to the pin member.

5. A bar support comprising two channel 55 members joined together by a flat part, a concave depression in the contiguous ends of the side walls of each member to embrace and clamp a bar when the two members occupy positions substantially at right angles to each other and laterally extending feet from near the mid-portion of one member. 60

In testimony whereof we hereunto set our hands.

WILLIAM C. BURRELL.
ROBERT R. ROBERTSON.
